UNITED STATES PATENT OFFICE.

HENRY MILLER, OF NEWARK, NEW JERSEY, ASSIGNOR TO THE W. C. EDGE JEWELRY COMPANY, A CORPORATION OF NEW YORK.

SAFETY DEVICE FOR JEWELRY.

1,100,389.

Specification of Letters Patent. Patented June 16, 1914.

Application filed December 15, 1913. Serial No. 806,660.

To all whom it may concern:

Be it known that I, HENRY MILLER, a citizen of the United States, residing at Newark, in the county of Essex and State of New Jersey, have invented certain new and useful Improvements in Safety Devices for Jewelry; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in safety devices for articles of jewelry, and the like, and the invention has reference, more particularly, to a safety device adapted to be associated with the meeting ends or portions of articles of jewelry, such as bracelets, necklaces, etc., which are constructed of flexible material; said safety device being adapted to be used in addition to the primary clasp or fastening means by which the meeting ends of the article of jewelry are joined.

The invention has for its principal object to provide a simple, cheap and easily manipulated safety device for grasping the meeting ends or portions of an article of jewelry, and retaining the same in their closed or joined relation against disunion in case the ordinary or primary clasping device should become unfastened, and when used in association with certain types of primary clasp, such as buckles and the like, preventing the free end of the article of jewelry from becoming disengaged from said buckle, or the like.

Other objects of the present invention, not at this time more particularly enumerated, will be clearly understood from the following detailed description of the same.

With the various objects of the present invention in view, the same consists, primarily, in the novel construction of safety device for jewelry, and the like, hereinafter set forth; and, the invention consists, furthermore, in the novel arrangements and combinations of the various devices and parts, as well as in the details of the construction of the same, all of which will be more fully described in the following specification, and then finally embodied in the clauses of the claim which are appended to

and which form an essential part of this specification.

The invention is clearly illustrated in the accompanying drawings, in which:—

Figure 1 is a face view of an article of 60 jewelry in the form of a bracelet which is equipped with the novel construction of safety device made according to and embodying the principles of the present invention; Fig. 2 is a detail longitudinal section 65 of the same, drawn on an enlarged scale, and taken on line 2—2 in said Fig. 1, looking in the direction of the arrow α ; Fig. 3 is a detail transverse section, also drawn on an enlarged scale, and taken on line 3—3 in 70 said Fig. 1; Fig. 4 is a large side elevation of said novel safety device removed from the article of jewelry; and Fig. 5 is a horizontal section of the same, taken on line 5—5 in said Fig. 4, looking downward. 75

Similar characters of reference are employed in all of the herein-above described views, to indicate corresponding parts.

Referring now to the said drawings, the reference character 1 indicates the body-portion of an article of jewelry in the form of a bracelet, the same being made of interwoven metallic strands, which, in this example, are braided together, the middle row of interstices 2, formed in the braided band, 80 serving as selectable receiving openings, for the purpose presently to be disclosed. Of course, it will be understood that I do not limit the use of my present invention to association with articles of jewelry, the body 85 of which is formed or constructed as above described, although I do wish to point out that my present invention is particularly serviceable when used with jewelry constructed of any flexible material. Secured 90 to one end of said body-portion 1, by solder or other suitable fastening means is the open frame-member 3 of a buckle-device, the tongue 4 of which is pivotally associated 95 therewith in the ordinary manner. Said 100 buckle-device provides the primary clasp means for joining and securing the meeting ends of the body-portion 1 when the same is caused to encircle and thus be worn upon the arm of its possessor. And to this end the 105 free-end portion 5 of the body-portion 1 inserted through the opening of the frame-member 3 of said buckle-device, and then the tongue 4 is inserted through a selected interstice 2 of said body-portion 1, which as 110

above indicated serves as a receiving opening therefor. It has been found that when the meeting ends of the body-portion 1 are thus clasped together by such a buckle-device, there is danger of the free end-portion 5 of the same becoming disengaged from the tongue 4, entailing the slipping of said free end-portion 5 through the frame-member 3, whereby the meeting ends are separated, and the article of jewelry therefore is in danger of dropping off the wearer's arm, and becoming lost. To prevent this occurrence, the novel safety device, comprising my present invention, serves most admirably. Said novel safety device comprises an open yoke-frame consisting of a bottom-bar 6, a top-bar 7, and interconnecting vertical or side bars 8. Secured within the opening of said yoke-frame, so as to extend transversely therethrough is a bridge-piece 9, the same being of any convenient form, and secured in place in any convenient manner. Said bridge-piece 9 divides the opening of said yoke-frame into two parts, thereby providing a lower receiving opening 10, and an upper receiving opening 11. Secured to the under side of said bridge-piece 9, by means of solder, or by any other convenient means, is a spring-arm 12, the body of which is bowed downwardly, as at 13, so as to project the arm into said lower receiving-opening 10. Preferably said spring-arm is secured by one end only, its opposite end being free, thereby rendering said spring arm more resilient or yielding, the inherent tension of the same, when the spring-arm is under compression, being sufficient, however, to enable the same to properly perform its function. It is also found preferable to provide said bridge-piece 9 with downwardly extending side-lips or flanges 14, which embracing the side-edges of said spring-arm 12, guard the same against undue lateral movement, which might tend to disconnect the same from said bridge-piece, said side-lips or flanges 14 being so disposed and arranged, however, as not to interfere with the proper vertical yielding movement or resiliency of said spring-arm 12.

The reference character 15 indicates a manipulatable spring gripping-member, which is mounted to extend transversely through said upper receiving opening 11 above said bridge-piece 9. Said gripping member 15 is secured to said bridge-piece 9, by passing one end of the same through an opening provided in said bridge-piece and beneath a struck up or raised portion 16 of said bridge-piece, said end then being soldered, or otherwise secured to the under side of said bridge-piece. As thus secured said gripping-member 15 extends in an upwardly inclined position transversely through said upper receiving-opening 11. One of said vertical or side bars 8 of said yoke-member is provided

with a vertically disposed opening or slot 17, through which the narrow neck 18 formed at the free-end of said gripping-member 15 extends. The extreme end of said gripping-member, at the outer extremity of said neck 18, is formed with an enlarged portion or head 19, which serves as a finger-piece for manipulating said gripping-member.

The operative association of said safety device constructed as above described with the article of jewelry may be accomplished as follows:—The body-portion 1 of the article of jewelry is passed through the lower receiving opening 10 of the yoke-member, until the latter is positioned near the buckle-device. When so positioned the spring-arm 12 bears upon said body-portion 1, and forces the same in frictionally held engagement with said bottom-bar 6 of said yoke-member, thereby retaining the latter in proper position. The free end-portion 5 of the body-portion 1 is now inserted through and engaged with the buckle-device in the manner already above described. When the meeting ends of said body-portion 1 are thus clasped together, the gripping-member 15 of the safety device is depressed, by pressing downwardly upon the finger-piece 19, this operation removes the said gripping-device 15 from obstructing position within said upper receiving-opening 11, so that said free end-portion 5 of the body-portion 1 may be inserted therethrough. When said free end-portion 5 is thus positioned to lie within said receiving-opening 11, the depressing force upon said gripping-member 15 is removed, and the spring tension thereof causes the same to move upwardly against said end-portion 10 holding the same in frictional engagement with said top-bar 7 of said yoke-frame, and consequently retaining the same against accidental removal from its connected relation with said buckle-device. When it is desired to remove said end-portion 5 from its gripped relation with said yoke-frame, the said gripping-member 15 is again depressed, thereby releasing said end-portion from frictional engagement with said top-bar 7, so that the same may be pulled through and out of said upper receiving-opening 11.

I am aware that some changes may be made in the several arrangements and combinations of the parts, as well as in the details of the construction of the same, without departing from the scope of my present invention. Hence I do not limit my invention to the exact arrangements and combinations of the parts as herein described, and as illustrated in the accompanying drawings, nor do I confine myself to the exact details of the construction of the said parts.

I claim:—

1. In a device of the kind described, an open yoke-frame, a bridge-piece mounted transversely in said yoke-frame to divide the same into an upper and lower receiving-opening, a vertically yieldable spring-arm secured to the under side of said bridge-piece so as to project into said lower receiving-opening, and a depressible spring-like gripping-member secured to said bridge-piece, and extending transversely through said upper receiving-opening, said yoke-frame having a vertical slot in one of its side-portions through which the free end 10 of said gripping-member extends, and a finger-piece at the exterior free-end of said gripping-member for manipulating the same.
2. In a device of the kind described, an open yoke-frame, a bridge-piece mounted transversely in said yoke-frame to divide the same into an upper and lower receiving-opening, a vertically yieldable spring-arm secured to the under side of said bridge-piece so as to project into said lower receiving-opening, downwardly extending longitudinal marginal flanges connected with said bridge-piece adapted to embrace said spring-arm and guard the same against lateral movement, and manipulatable gripping means mounted on said bridge-piece

and extending laterally through said upper receiving opening.

3. In a device of the kind described, an open yoke-frame, a bridge-piece mounted transversely in said yoke-frame to divide the same into an upper and lower receiving-opening, a vertically yieldable spring-arm secured to the under side of said bridge-piece so as to project into said lower receiving-opening, downwardly extending longitudinal marginal flanges connected with said bridge-piece adapted to embrace said spring-arm and guard the same against lateral movement, and a depressible spring-like gripping-member secured to said bridge-piece, and extending transversely through said upper receiving-opening, said yoke-frame having a vertical slot in one of its side-portions through which the free end 40 of said gripping-member extends, and a finger-piece at the exterior free-end of said gripping-member for manipulating the same.

In testimony, that I claim the invention set forth above I have hereunto set my hand this 9th day of December, 1913.

HENRY MILLER.
